Primary Examiner — Joseph Kukella*Assistant Examiner* — Darryl J Dardenne(74) *Attorney, Agent, or Firm* — Alan D. Kamrath; Karin L. Williams; Mayer & Williams PC(57) **CLAIM**

The ornamental design for an igniter, as shown and described.

DESCRIPTION

FIG. 1 is a perspective view of an igniter showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The shaded surfaces and the solid lines represent the claimed portions of the design.

The broken lines depict portions of the igniter in which the design is embodied that are not considered part of the claimed design.

1 Claim, 7 Drawing Sheets(56)
